UNITED STATES PATENT OFFICE.

ROBERT JACOB GÜLCHER, OF BERLIN, GERMANY.

THERMO-ELECTRIC BATTERY

SPECIFICATION forming part of Letters Patent No. 472,261, dated April 5, 1892.

Application filed June 18, 1891. Serial No. 396,782. (No model.)

To all whom it may concern:

Be it known that I, ROBERT JACOB GÜLCHER, engineer, a subject of the King of Prussia and German Emperor, residing at Berlin, in the 5 Kingdom of Prussia and German Empire, have invented certain new and useful Improvements in Thermo-Electric Batteries; and I do hereby declare the following to be a full, clear, and exact description of the invention, such as will enable others skilled in the art to which it appertains to make and use the same.

This invention relates to thermo-electric batteries; and it consists in the novel construction and combination of the parts hereinafter fully described and claimed.

In carrying out this invention the elements which are subjected to a less degree of heat, and which consequently develop less electro- 20 motive force, are made of less resistance than the elements which are subjected to a greater degree of heat, and the difference in the resistances of the elements is made substantially proportional to the differences in their tem- 25 peratures. This change in resistance may be accomplished by making the elements of larger size to lessen their resistance, or by changing the metal or alloy of which they are composed.

30 In the accompanying drawings, Figure 1 shows a vertical section of a thermo-electric battery constructed according to the present invention. Fig. 2 is a sectional plan view of a single row of elements. Figs. 3 and 4 are 35 detail plan views of modifications of two of the elements.

a a is the heating-chamber, around which are arranged the wheel-shaped rows of elements *b' b² b³*, &c., which are placed one above 40 the other. The points of connection *c c* of the separate elements themselves form the inner wall of the heating-chamber. The separate elements, as also the rows of elements, are insulated from each other in a suitable manner 45 by means of layers *e* of material that is at the same time a bad conductor of heat, such as a mixture of fossil-meal and asbestos. The cooling of the soldered parts *d d* is effected by copper bands *f f*, soldered thereto, which 50 are connected by wires to hoops of insulat-

ing material *g g*, such as ebonite, paraffined wood, &c. The proportion between the internal resistance and the electro-motive force is rendered constant in each row of elements by making the separate elements of equal size 55 only so far as the temperature of the heating-chamber is about at the same height, such as from *b'* to *b⁴*. From the point where the temperature begins to decrease the sections of the elements are made to gradually increase, be- 60 ing for this purpose increased in height, while the other dimensions remain the same, such as from *b⁵* to *b¹⁰*.

The heating-chamber *a a* is heated by means of a Bunsen burner *l* of hollow cylindrical 65 form, which imparts to the chamber a constant high temperature over a tolerably-extended surface, such as from *b'* to *b⁴*. It will be readily understood that the thermo-electric pile could also be otherwise heated, such as 70 by a petroleum-burner or by a coke-fire. The rows of elements rest in the present instance upon a suitable stand fixed together with the burner *i k* upon a base-plate *o*. On the rings *g* of the top row of elements is placed a conical hood *h h* of sheet-iron, with a central outlet, which can be connected in any convenient manner with a chimney in order to expose the cooling-bands *f f* to a strong current of air. The hood *h h* is provided with lugs, through 75 which and through corresponding lugs on the bottom-stand pass screw-bolts for securing the parts firmly together.

Fig. 2 shows a sectional plan of a single row of elements. *c c* are the connecting-pieces or 80 intermediate contacts to be heated, which are made of a good conductor of heat, such as copper. On one side thereof the positive elec- 85 trodes *p p* of sheet-nickel are brazed, while the negative electrodes *b b* of an alloy—such 90 as antimony and zinc—are cast into hollows of the said contacts. The separate elements, which are placed closely side by side at their connecting parts *c c*, are insulated from each other by thin strips of mica *q q*. The remaining free space between the elements is filled 95 with a bad conductor of heat *e e*, with which the elements are also covered at top and bottom. There are two copper cooling-bands *f f* connected to each element, whereby an effect- 100

ive cooling of the outer soldered points *d d* is produced. *g* is the ring of vulcanite or other material, to which the outer ends of the cooling-bands are attached.

5 The drawings show all the elements connected in series. They may, however, according to circumstances, be all or partly connected in parallel. The mode of connecting the elements in the one row, however, determines the mode of connection of the other rows in the same pile. The rows themselves must always be connected in series. Several rows of elements could be combined together in groups of equal electro motive force, and 15 these groups may then be connected in parallel.

Figs. 3 and 4 show two of the new elements with the extended intermediate contacts *c c*. *b b* are the negative electrodes of easily-fusible 20 metal, which are cast around the dovetailed plugs *c'* of the intermediate contacts. The positive electrodes consist, for example, of strips of sheet-nickel *p p*, and they are connected with the ends of the intermediate contacts either by brazing them on, as at Fig. 3, or by casting them on, as at Fig. 4. Only the ends *c c*, connected to the positive electrodes, are directly subjected to the temperature of the source of heat, while the ends *c'*, connected 25 to the negative electrodes, only transmit such heat to the latter as is conducted from *c* to *c'* through the intermediate contact. For this purpose the elements may be, for example, arranged in the same manner as shown at Fig. 30 2, the entire free space both between the extended intermediate contacts and also between the electrodes being filled with an insulating bad conductor of heat. By suitably proportioning the extended intermediate contact a 35 considerable difference of temperature may be maintained between the two points *c* and *c'*, so that if, for example, the positive electrode *p* has a temperature of, say, 500° centigrade and above the negative electrode at 40 *c'* only receives a heat of, say, 300° centigrade, which temperature is below the melting-point of the alloy employed.

What I claim is—

1. In a thermo-electric battery, the combination, with a source of heat, of elements having different internal resistances, said ele-

ments being arranged in a graduated series, the elements of less internal resistance being arranged at a distance from the source of heat so that the resistance of each element is substantially proportional to the temperature to which it is subjected, and all the said elements of different internal resistances being connected in series, substantially as and for the purpose set forth. 55 60

2. In a thermo-electric battery, the combination, with a source of heat, of elements of different sizes, said elements being arranged in a graduated series, the larger elements, which have less internal resistance, being arranged at a distance from the said source of heat so that the resistance of each element is substantially proportional to the temperature to which it is subjected, and all the said elements of different sizes being connected in 65 70 series, substantially as and for the purpose set forth.

3. In a thermo-electric battery, the combination, with a central source of heat, of elements arranged in rows around the said source 75 of heat, the said rows being arranged in a graduated series, the elements in the rows which are more remote from the source of heat being of less internal resistance, substantially in proportion to the lower temperature to 80 which they are subjected, and the said rows of elements having different resistances being connected in series, substantially as and for the purpose set forth.

4. A thermo-electric element consisting of 85 a negative electrode of fusible metal, a positive electrode of refractory metal, and an intermediate metallic contact-piece having its opposite ends secured to the said electrodes, said contact-piece being adapted to be heated 90 only at that end of it to which the said positive electrode is connected and proportioned so that a considerable difference in the temperature of its ends is constantly maintained, substantially as and for the purpose set forth. 95

In testimony whereof I affix my signature in presence of two witnesses.

ROBERT JACOB GÜLCIER.
